BYRON J. PEPPER, OF FORT WAYNE, INDIANA, ASSIGNOR TO TOKHEIM OIL TANK AND PUMP COMPANY, OF FORT WAYNE, INDIANA.

LOCKING DEVICE FOR DISPENSING APPARATUS.

Application filed January 10, 1927. Serial No. 160,101.

This invention relates to improvements in locking devices for dispensing apparatus of that class wherein a pump is housed in the pedestal of the apparatus, which pump is employed for withdrawing gasoline from an underground reservoir and delivering it into a measuring vessel positioned on the pedestal, and from which vessel the gasoline is subsequently dispensed to the patron in 10 quantities regulated by a control mechanism.

The object of the invention is to provide a device for locking and unlocking a door in the pedestal in which the pump is contained, actuated by the control mechanism by which 15 liquid is dispensed from the measure, and to provide also a locking means for the control mechanism, whereby operation of the pump is prevented when the control mechanism is locked. Another object of the improvement 20 is to provide means to prevent unauthorized operation of the filling means for the measure when the control mechanism for dispensing liquid from the measure is locked.

These objects are accomplished by the construction illustrated in the accompanying drawings, in which:—

Fig. 1 is a fragmentary front elevation of a dispensing apparatus including that portion of the pedestal thereof containing a 30 pump, and the control mechanism;

Fig. 2 is a section of a portion of Fig. 1 projected therefrom at right angles thereto;

Fig. 3 is a fragmentary cross sectional view of Fig. 1 on the line 3—3 thereof;

Fig. 4 is a front elevation similar to Fig. 1 with the doors of the pedestal and control mechanism in open position; and

Fig. 5 is a fragmentary cross sectional view projected from Fig. 4.

The characters appearing in the description refer to parts shown in the drawings and designated thereon by corresponding characters.

The invention consists primarily in the 45 means for preventing operation of the pump by which the measuring vessel of the dispensing apparatus is filled, in conjunction with the operating mechanism by which the dispensing of liquid from the measure is controlled. The construction shown consists of a pedestal 1 in which is installed a hand operated pump 2, the pedestal having a hinged door 3 upon the opening of which access is gained to the pump. The pump 2 has a

plunger rod 4 provided with a cross head 5, 55 at its outer end, to which is connected an operating lever 6 by which the pump is actuated. The lever 6 is so located with respect to the pedestal that when the door 3 is open it may be moved to and fro through the door 60 opening 7 in the pedestal.

A bolt 8 projects from the head end of the pump 2 and has mounted thereon a tilting lock member 9 that has engagement with the cross-head 5 when the latter is in its innermost position, there being a lug 9' on said member to obstruct outward movement of said cross-head. The lock member has also an arm 10 provided with an adjustable stud 11 that has engaging relation with the 70 foot 12 on the bottom of a vertically movable lock-bar 13, which lock-bar is positioned on studs 14 that project from the inner wall of the pedestal 1 adjacent the door opening.

The door 3 has upon its inner face projecting hooks 15 that have locking engagement with the bar 13 when said door is closed and the lock-bar is in its lowermost position, there being openings 16 in the wall 80 of the pedestal and the lock-bar for the reception of said hooks respectively.

The control mechanism for the dispenser may be of any suitable construction, an example of which is herein shown consisting of a control box 17 mounted upon the side of 85 the pedestal and provided with a master lever 18 and a hinged lid 19, there being a lock 20 controlling said lid, which lid when locked, prevents operation of the lever 18.

The measuring vessel, and connections between the master lever 18 and the vessel by which dispensing operations are controlled, are not herein shown as their particular constructions are immaterial to the present invention, but may be in any known form capable of proper operation by manipulation of the master lever 18.

A reciprocal bar 21 in the control box is actuated by the master lever 18, and a rock-bar 22 in the pedestal is so formed and disposed as to turn upon its pivot 23 in one direction or the other accordingly as the master lever is swung inwardly or outwardly upon its pivot 24. The lock-member 9 has a crank arm 25 that is connected with the rock-bar 22 by a rod 26 so that as the rock-bar is tilted, the lock member 9 is actuated accordingly. Thus, when the master lever 18 is

moved to its inward position, as shown in Fig. 4, the lock-member 9 is tilted so as to clear the cross-head 5 on the plunger rod and permit operation of the pump; and also the 5 lock-bar 13 is elevated by engagement of the stud 11 on the lockmember with the foot 12 on the lockbar, so that the lockbar is thereby disengaged from the hooks 15 to permit 10 opening of the door. The bottom face 5' of the cross-head 5 extends over the lug 9' on the lock-member 9 during operation of the pump, or when the pump handle 6 is in any other than its innermost or locking position, and the lock-member 9 is thereby prevented 15 from being tilted into locking position, and consequently the master lever 18, through its connections with said lock member, is prevented from being actuated during operation of the pump, or while the pump handle is in 20 any other than its innermost or locking position. In this manner simultaneous operation of the master lever and the pump is prevented.

In the operation of the invention, the lid 25 on the control box is first opened, which permits the master lever 18 to be actuated, which lever is then tilted toward the pedestal, causing the reciprocal bar 21 to tilt the rock-bar 22, thereby causing the lock member 9 to 30 move out of the path of the cross-head on the pump mechanism so as to permit operation of the pump. As the lock-member is thus moved, the stud on the lug 10 of the lock-member bears upwardly against the foot of 35 the lock-bar, so that said lock-bar is raised out of engagement with the hooks 15 on the door of the pedestal, thus permitting the door 3 to be opened. The pumping mechanism is then operated by actuating the 40 pump handle 6. When the cross-head of the pump is drawn by the handle from its innermost position, it passes over the lug 9' on the lock-member and prevents movement thereof which accordingly prevents movement 45 of the master lever. In this manner simultaneous operation of the pump and the master lever is prevented. By moving the pumping handle to its innermost position, as indicated in Fig. 2, the cross-head is accordingly moved beyond the lug 9' on the lock-member, thus permitting the lock-member to tilt and the master lever to be freely manipulated. However, when said lock-member is tilted to its locking position, the lug 9' obstructs the cross-head preventing operation of 55 the pump. Upon movement of the door 3 to its closed position the hooks 15 become re-engaged by the lock-bar 13, and the door is accordingly locked and access to the pump 60 mechanism is prevented.

What I claim is:—

1. In liquid dispensing apparatus having a pedestal and a pump housed therein, said pedestal having a door opening through which said pump is accessible, a door for closing said opening; a control box on the pedestal provided with a lid, a control mechanism for the dispensing apparatus, including a master lever fulcrumed in said box and locked against movement by said lid when the lid is closed; a tilting lock member operable to lock the pump when the operating handle of the pump is in its innermost position and which member is immovable when said pump handle is in any other than its innermost position; a lock for said door controlled by said tilting lock member; and a mechanism actuated by said master lever connected with said lock-member so arranged as to prevent manipulation of said master lever when said lock-member is out of locking engagement with said pump. 75

2. In liquid dispensing apparatus having a housing with a door opening therein; a pump in said housing accessible through said door opening; a lock controlled door for closing said opening; a control mechanism for said dispensing apparatus, including a master lever in supported connection with the housing; a lock member controlling the door lock and operable to lock the pump when the operating handle of the pump is in its innermost position, and which member is immovable when said pump handle is in any other than its innermost position; and a mechanism connecting said master lever with said lock member so arranged that manipulation of said master lever is prevented when said lock-member is out of locked engagement with said pump. 90

3. In a liquid dispensing apparatus having a filling means and a control mechanism, a locking member for said filling means operably connected with said control mechanism; and a member on the filling means that prevents operation of said lock member and the control mechanism connected therewith during operation of said filling means. 105

4. In liquid dispensing apparatus having a filling means and a control mechanism, a locking mechanism related with said filling means and control mechanism, which locking mechanism prevents operation of said control mechanism during operation of said filling means and which permits operation of said control mechanism when said filling means is locked by said locking mechanism. 110
